SAFE SCREEN SUPPORT

John Whalen, Brooklyn, N. Y.

Application September 16, 1944, Serial No. 554,482

3 Claims.

(Cl. 160—107)

1

This invention relates to the combination with a window screen of means for preventing the screen from being pushed outwardly, to expose a child or other person to peril, and means for preventing the screen from being accidentally forced or drawn inwardly into the room, so as to leave the window opening wholly unguarded, and thereby exposing a child or other person who is careless at the window opening to injury or death.

The invention also embraces an attachment which can be mounted on one of the sliding frames of an adjustable window screen to prevent the screen from being forced outwardly, and another and similar attachment which can be mounted on the companion sliding window screen to prevent the window screen from accidentally falling or being drawn into the room, so that the screen will always remain in its guarding position in the window opening.

With the above and other objects in view the invention relates to certain new and useful constructions, combinations and arrangements of parts, clearly described in the following specification and fully illustrated in the accompanying drawing, in which:

Fig. 1 is a view in elevation, showing the manner of attaching the safety devices to the window screen.

Fig. 2 is a detail vertical sectional view, taken on line 2—2 of Fig. 1, looking in the direction of the arrows.

Fig. 3 is a similar view, taken on line 3—3 of Fig. 1, looking in the direction of the arrows.

Fig. 4 is a rear elevation.

Fig. 5 is a front elevation.

Fig. 6 is an end view.

Referring to the accompanying drawing, which illustrates the practical construction of my invention, 5 designates any standard window frame and 6 the lower window sash, which normally slides up and down in the frame 5 for ventilation and other reasons.

In the window opening provided by raising the lower window sash 6 a conventional adjustable window screen 7 is disposed, which consists of the companion screen frame sections 8 and 9, which are arranged to slide upon each other, for the purpose of varying the horizontal distance between the outer ends of the two frame sections, so that the combined screen may be fitted into the window frame.

In normal practice the ends of the window screen sections are disposed against the vertical sides of the window frame, but when pressure is

2

applied against the inside of the screen it will easily fall out of the window opening, thus leaving the window opening wholly unguarded. The same applies to the tendency of the window screen to fall or be drawn into the room, and in this case the window frame opening is also left wholly unguarded.

To prevent the window screen from being accidentally displaced either outwardly or inwardly, 10 I provide an attachment for each screen section or frame, which has a stop flange, adapted to engage one side of the lower rail of the sash 6, this flange being formed on a bracket or C-shaped sleeve adapted to slidably engage the upper cross bar of the screen frame.

The attachment for the screen frame section 8 consists of the C-shaped sleeve or bracket 10, which is formed with a struck-out tongue or flange 11, which is of L-shaped construction, and 20 which is offset from the vertical axis of the sleeve 10.

The bracket or sleeve 10 is mounted on the upper cross bar of the screen frame section 8, so that the flange or tongue 11 will engage the 25 lower edge and inner surface of the lower rail or cross bar of the sash 6.

The screen frame section 9 is provided with a similar C-shaped bracket 10a, which is formed with a struck-out flange 11a, and this flange is 30 also of L-shaped construction and is adapted to engage the bottom face of the sash and the outer face of the lower cross rail thereof.

The sliding screen sections may be adjusted on each other, in fitting the window screen under 35 the sash, so as to completely fill the window opening, and the two safety guards will slide on the lower end of the sash to permit any necessary adjustment of the window screen in the window opening.

40. But in the event that pressure is applied against the inside of the screen, the guard flange 11 will prevent the screen from being displaced outwardly. In the event that a pulling effort is applied to displace the screen inwardly, the guard flange 11a will prevent the screen from being 45 displaced inwardly.

The attachment may be readily mounted on the screen section, and is secured in place by means of the screw 12, which is extended through 50 the central portion of the C-shaped sleeve or bracket into the screen section engaged. This screw connection prevents the bracket from accidentally shifting on the screen frame.

My invention is particularly useful in protecting children from falling out of windows, as a

result of the window screens being pushed outwardly or displaced inwardly, so as to leave the window openings wholly unguarded by the screen.

It is understood that various changes in the details of construction may be provided, without departing from the spirit of the invention, as defined in the claims hereof.

Having described my invention, I claim and desire to secure by Letters Patent:

1. The combination with a window screen having relatively slidable frames provided with screen sections, of a C-shaped member adapted to partly enclose an upper side bar of each frame member and provided with a struck-out L-shaped flange adapted to slidably engage the lower edge of a sash under which the window screen is to be positioned.

2. The combination with a window screen comprising relatively slidable frame sections, each frame section having a screen, and each frame section having an upper bar, of a C-shaped member mounted on the upper bar of each frame section and adapted to resist displacement from the bar in all directions, each C-shaped member being secured to the bar by a fastener extending through the same into the bar, and an L-shaped

flange struck from the C-shaped member and adapted to engage the lower end of a window sash under which the window screen is to be positioned.

3. The combination with a window screen comprising relatively slidable frame sections, each frame section including an upper bar and a screen-section, a C-shaped member largely enclosing a portion of the upper bar of each frame section and providing an L-shaped flange engaging the upper edge of the upper bar of the window screen frame section and an L-shaped flange engaged with the lower edge of said bar, and an L-shaped flange struck from the first-named 15 L-shaped flange and extending above and laterally of the said first-named L-shaped flange, and adapted to have sliding engagement with the lower end of a window sash under which the window screen is positioned, said first and second-named L-shaped flanges being adapted to resist vertical displacement of the C-shaped member from the upper frame bar in either direction, and the last-named L-shaped flange being adapted to engage only one side of the window sash.

JOHN WHALEN.
